UNITED STATES PATENT OFFICE.

JOHN J. BLOXSM AND ELMER E. MYERS, OF BROOKVILLE, PENNSYLVANIA.

GLASS-DRAWING APPARATUS.

1,375,818.

Specification of Letters Patent. Patented Apr. 26, 1921.

Application filed September 2, 1919. Serial No. 321,103.

To all whom it may concern:

Be it known that we, JOHN J. BLOXSM and ELMER E. MYERS, residing at Brookville, in the county of Jefferson and State of Pennsylvania, citizens of the United States, have invented or discovered certain new and useful Improvements in Glass-Drawing Apparatus, of which improvements the following is a specification.

10 This invention relates to apparatus for drawing glass cylinders in which the air for blowing the cylinder is supplied at the point of draw, and has particularly to do with apparatus in which a carrier is provided with a molten glass container and is movable to cause the container to be brought to and from drawing position.

The object of the invention is to improve the air supplying apparatus to the end that 20 adequate conduit connections may be automatically made and broken at the point of draw, and to the further end that the air supply conduit may be automatically opened to periodically free it of accumulations of broken glass or other foreign matter.

In the accompanying sheets of drawings which form part of this specification the preferred embodiment of the invention is illustrated. Figure 1 is a combined elevation and central sectional view of glass drawing apparatus; Fig. 2 a plan view of the carrier or turn table shown in Fig. 1, the general plane of view being indicated by the line II-II, Fig. 1; Fig. 3 a side view 30 to enlarged scale of means used for connecting the air conduits; Fig. 4 a view of the right side of Fig. 3; Fig. 5 a sectional view taken on the line V-V, Fig. 3; Fig. 6 a side view of the means for opening the bottom of the air supply conduit; and Fig. 7 a plan view of the parts shown in Fig. 6.

In the apparatus shown in the drawings, the carrier for the molten glass containers is a turn table 1, and the containers are 45 ranged upon the top of the table are in the form of pots 2 into which molten glass is ladled prior to a draw. After a cylinder has been drawn from a pot of glass at the drawing station, the table is turned so that 50 the pot previously at the drawing station is moved to a pot-heating station, at which the glass remaining in the pot is melted and subsequently drained from the pot. The drawing of the glass may, as shown in Fig. 55 1, be effected by a bait 3 secured to a frame

4 vertically movable upon guides 5 by means of a hoisting cable 6. At the pot-heating station, or stations (there being two such stations indicated in the drawings), the pots are heated by gas or other 60 fluid fuel burners 7, a hood 8 being provided to confine the heat.

For blowing a cylinder at the drawing station, air is supplied through a conduit 9, which is in fixed position at the drawing 65 station, and a conduit 10, one of which extends centrally through each pot 2 and through the portion of the table below it. When a pot is at the drawing station, its conduit 10 registers with the fixed conduit 70 or supply pipe 9. Means, operated by the movement of the table, are provided for making and maintaining the connection between these conduits. As shown particularly in Figs. 3, 4 and 5, one of the conduits, 75 preferably the conduit 9, is provided with a sleeve 11 having a laterally projecting flange 12, such sleeve telescoping with, and being longitudinally movable within, the conduit 9. To move the flanged sleeve upwardly into engagement with the conduit 10, there is preferably provided a pivoted lever 13, one end of which has a yoke 14 adapted to engage the sleeve. Attached, 80 preferably to the lower face of the turn table 1, there are a series of springs 15, one adjacent to each of the pots 2. As a pot approaches the drawing station, the spring 15 adjacent to such pot engages the outer end of the lever 13 and moves it downwardly with the result that the inner end of the lever raises the sleeve 11, 12, and holds it yieldingly against the bottom of the conduit 10 as long as the pot is in drawing 85 position. The springs 15 are preferably placed at the outer edge of the turn table, as indicated in the drawing, so that they 90 will not be subjected to the heat of the burner 7.

In glass drawing apparatus of the general 100 character contemplated herein it occasionally happens that particles of broken glass fall through the conduit 10 into the conduit 9, and such particles interfere with proper blowing and drawing cylinders. To overcome this difficulty means are provided for automatically opening the air supply conduit to permit the discharge of broken glass from it. To such end the conduit 9 is 105 preferably provided with a downwardly ex- 110

tending projection cut obliquely at its lower open end, as shown particularly in Figs. 6 and 7. Pivoted to the end of this projection, there is a closure 17 provided with an 5 arm 18 attached to one end of a second and counterweighted arm 19. The other end of the arm 19 has a pin-and-slot connection with the lower end of vertically reciprocable rod 20, the upper end of which is 10 adapted to be engaged by an abutment 21 attached to the lower face of the table 1. While the table 1 may be provided with but a single abutment 21, there are preferably three such abutments arranged one between 15 each of the pots 2 so that the conduit extension 16 may be opened each time the table is turned to advance the pots a single station.

In operation, the closure 17 is held normally in closed position (indicated in dotted lines in Fig. 6) by reason of the counterweight on the rod 19. When the table 1 is turned, an abutment 21 presses the rod 20 downwardly, with the result that the closure 25 is moved to the full line position indicated in Fig. 6, in which position the bottom of the conduit extension 16 is opened to permit the discharge of whatever broken glass or other foreign articles may be in it.

According to the provisions of the Patent 30 Statutes, we have described the principle and operation of our invention together with the form of construction which we now consider to represent the best embodiment 35 thereof. However, we desire to have it understood that, within the scope of the appended claims, our invention may be practiced by other forms of construction than that specifically shown and described herein.

We claim as our invention:

1. In apparatus for drawing glass cylinders, the combination of a turn table provided with a molten glass container, an air conduit having an open end below said table 45 and extending through said container, an air supply pipe having an open end below the table, a sleeve at the end of said pipe longitudinally movable thereof to register with the end of said conduit, a pivoted lever 50 engaging said sleeve, and a spring secured

to said table and adapted upon the rotation thereof to engage said lever to move said sleeve into engagement with the open end of said conduit.

2. In apparatus for drawing glass cylinders, the combination of a carrier provided with a molten glass container and movable to and from drawing position, an air conduit extending from below said carrier through said container, an air supply pipe below said carrier and adapted to register with said conduit when the container is in drawing position, and means coördinated with the movement of the container for opening the air supply pipe to permit the discharge of 65 glass therefrom.

3. In apparatus for drawing glass cylinders, the combination of a turn table provided with a molten glass container, an air conduit extending through said table and container, a vertically disposed air supply pipe below said table provided with a bottom discharge opening, the top of said pipe being adapted to register with the bottom of said conduit when the glass container is 70 in drawing position, a closure for said discharge opening, and means coördinated with the movement of said table for opening said closure to permit the discharge of broken 75 glass from the air supply pipe.

4. In apparatus for drawing glass cylinders, the combination of a turn table provided with a molten glass container, an air conduit extending through said table and container, a vertically disposed air supply 85 pipe below said table provided with a bottom discharge opening, the bottom of said conduit being adapted to register with the top of said pipe when the glass container is in drawing position, a pivoted closure for 90 said discharge opening, a lever secured to said closure, and a lever-engaging abutment borne by said table and adapted upon the rotation of the table to move said lever to open said closure.

In testimony whereof we have hereunto set our hands.

JOHN J. BLOXSOM.
ELMER E. MYERS.
